UNITED STATES PATENT OFFICE.

NEWTON FELLABAUM, OF SPERRY, OKLAHOMA.

ADJUSTABLE JACK PLATE.

Application filed November 13, 1922. Serial No. 600,782.

To all whom it may concern:

Be it known that I, NEWTON FELLABAUM, a citizen of the United States, residing at Sperry, in the county of Tulsa and State of Oklahoma, have invented certain new and useful Improvements in Adjustable Jack Plates; and I do declare the following to be a full, clear, and exact description of the invention, such as will enable others skilled in the art to which it appertains to make and use the same.

My invention relates to improvements in supporting plates for the oscillatory jacks used in connection with oil well pumps, the object of the invention being to provide an extremely simple and inexpensive device of this character which may be adjusted horizontally on a pivotal axis for the purpose of properly alining the jack with the other equipment, with which it co-operates.

With the foregoing in view, the invention resides in the novel subject matter herein-after described and claimed, the description being supplemented by the accompanying drawing.

Figure 1 is a side elevation of my invention and a portion of a jack thereon.

Figure 2 is a top plan view.

In the drawing above briefly described, the numeral 1 designates a portion of a well known oil well jack having the usual transverse horizontal fulcrum 2. I provide an elongated bed plate 3 to support this fulcrum, the upper surface of the plate being provided with a groove 4 extending substantially throughout its length to receive the fulcrum, the ends of the groove being closed by upstanding lugs 5 which prevent endwise movement of said fulcrum. At one side of the groove 4, the upper side of the bed plate 3 is provided with a pair of hooks 6 to engage the fulcrum 2 while guard ribs 7 may well be formed at the other side of said groove. Also, the upper surface of the bed plate may be thickened wherever desired for reinforcing purposes, as indicated on the drawing. One of these thickened portions, designated by the reference character 8, is formed with a slot 9 parallel with the groove 4 and disposed between this groove and one

edge of the plate. A bolt 10 is passed through this slot for connecting the bed plate 3 pivotally with a suitable foundation 11 upon which it rests, whereby said plate may be horizontally swung and adjusted to properly aline the jack with the other parts with which it co-operates.

Opposite ends of the plate 3 are provided with outwardly projecting integral lugs 12 having openings 13 formed horizontally therethrough, said openings being widened toward one end to permit horizontal adjustment of a pair of anchor rods 14 which pass therethrough. The ends of these rods, remote from the bed plate 3 are provided with anchors 15 which are preferably of L-shape, to hook over one edge of the foundation 11, the upright arms of said anchors having openings through which the anchor rods 14 pass. The numerals 16 designate washers which are thinned toward one edge and interposed between the nuts 17 of the rods 14 and the lugs 12. Before tightening of the nuts, the washers may be set so that they will contact both with the lugs and the nuts, giving a firm bearing surface, regardless of the angle to which the rods 14 are swung with respect to the bed plate.

By the use of the invention, it will be seen that after bolting the bed plate 3 to the foundation by means of the bolt 10, the rods 14 may be adjusted so that the jack may be properly positioned to operate most advantageously. The bolt 10 and the nuts 17 may then be finally tightened to securely lock the device in place.

The bed plate is of extremely simple and inexpensive construction, yet it will be highly efficient and in every way desirable. As excellent results may be obtained from the details disclosed, they are preferably followed. However, within the scope of the invention as claimed, numerous minor changes may be made.

I claim:

1. A device of the character described comprising a bed plate adapted to pivotally support a jack, a pivot between the ends of said plate for connecting the latter with a foundation to permit horizontal swinging

thereof, the ends of said plate being provided with projecting lugs having tapered openings formed horizontally therethrough, and a pair of anchor rods received in said openings, said rods having anchors to engage the foundation.

2. A structure as specified in claim 1; said

anchors being of L-shaped form to hook around one edge of the foundation and having openings in their upright arms receiving said rods.

In testimony whereof I have hereunto affixed my signature.

NEWTON FELLABAUM.
